UNITED STATES PATENT OFFICE.

PHILIP H. FRAHER, OF HOLBROOK, MASSACHUSETTS, ASSIGNOR TO UNITED SHOE MACHINERY CORPORATION, OF PATERSON, NEW JERSEY, A CORPORATION OF NEW JERSEY.

CONNECTION OF PIECES OF SHOE STOCK.

Application filed January 28, 1918. Serial No. 214,128.

To all whom it may concern:

Be it known that I, PHILIP H. FRAHER, a citizen of the United States, residing at Holbrook, in the county of Norfolk and 5 State of Massachusetts, have invented certain Improvements in the Connection of Pieces of Shoe Stock, of which the following description, in connection with the accompanying drawings, is a specification, like 10 reference characters on the drawings indicating like parts in the several figures.

This invention relates to the connection of pieces of shoe stock in the manufacture of shoes and more particularly to the assembling of pieces of shoe stock and the formation of a metallic seam or seams connecting said pieces.

An object of the invention is to improve the connection of pieces of shoe stock by 20 the use of metallic fastenings to form a tight and durable attaching or reinforcing seam which readily permits the flexure of the connected parts in the direction of the seam to accommodate the movements of the 25 foot of the wearer, and which prevents the ripping of the attached parts from each other. In the practice of the invention, a seam is produced which maintains a wide strip of the attached piece of shoe stock 30 against flexure in a direction transverse to the line of the seam and the edge of the piece of shoe stock, making practically impossible the opening up of the seam. The 35 making of such a seam in attaching heel seats is of particular importance as will be more fully explained hereinafter.

An important feature of the present invention resides in inserting metallic fastenings having heads which are relatively long 40 as compared to their widths with the long dimensions of their heads disposed transversely of the edge of the stock in accordance with a systematic arrangement producing a tight seam capable of easy flexure in 45 the direction of the seam. Preferably and as illustrated, the shanks of the fastenings are formed with their longest transverse cross-sectional dimensions in the direction of the longest dimensions of their heads 50 and with their smallest transverse cross-sectional dimensions in the direction of smaller dimensions of the heads.

In accordance with another feature of the invention, the metallic fastenings used are

formed with their head portions extending 55 from one side only of their shanks and are inserted into the shoe stock so that their head portions extend toward the edge of the attached piece of shoe stock, the heads of the fastenings being preferably undercut 60 so that the under sides of the heads which extend at an angle to the upper portions of the shanks of the fastenings overhang the strip of shoe stock lying between the edge of the shoe stock and the line of 65 the seam formed by the fastenings.

A further and more particular feature of the invention consists in clinching the points of the fastenings into the shoe stock in a direction away from the edge of the 70 piece of stock and away from the sides of the shanks of the fastenings from which the heads project. This feature of the invention permits the heads of the fastenings to be brought close to the edge of the piece of 75 shoe stock in which the seam is formed, thus reducing the width of the strip of stock between the edge of the piece of stock and the attaching or reinforcing seam.

In attaching pieces of stock together for 80 bottoming shoes it is sometimes desirable to position the fastenings with their shanks inclined to the edges of the pieces of shoe stock. Such arrangement of the fastenings permits the heads thereof to be brought as 85 close as possible to the edge of the attached piece of shoe stock, at the same time permitting the points of the fastenings to be clinched firmly into the stock.

Other objects and features of the invention will be apparent as the description proceeds.

In the drawings:

Fig. 1 illustrates the application of the improved method to the attachment of a 95 welt to an upper and insole;

Fig. 2 is, in part, a cross section taken along the line 2—2 of Fig. 1 showing the points of the welt attaching fastenings clinched in a direction away from the edge 100 of the insole, and illustrating further the application of this invention to the attachment of an outsole to the welt;

Fig. 3 is a cross section taken along the line 3—3 of Fig. 1 showing the points of the 105 fastenings clinched in the direction of the edge of the shoe and of the seam;

Fig. 4 illustrates the application of the

improved method to the attachment of an outsole to an upper and insole;

Fig. 5 illustrates the application of the improved method to heel seat nailing;

Fig. 6 illustrates the application of the improved method to channel nailing around the toe of the shoe;

Fig. 7 illustrates diagrammatically the application of this invention to heel seat 10 nailing;

Fig. 8 indicates diagrammatically the kind of seam that would be formed if string 15 nails inserted in accordance with present methods were used for heel seat nailing;

Fig. 9 illustrates the types of fastenings 20 preferably employed in the practice of the invention.

In carrying out the method of this application, an insole designated A in the drawing is tacked to the bottom of a last in the usual manner. The upper B is then slipped over the last, and the margin of the upper B is pulled over the edge of the insole A 25 and tacked thereto. In the making of a welt shoe, a welt C is then attached to the upper and insole by metallic fastenings D. As shown in Figs. 1 and 9 of the drawings, the fastenings D are formed with heads 30 which are relatively long as compared to their widths, and with tapering shanks having their transverse cross-sectional dimensions indicated at s (Fig. 9) in the plane of the long dimensions of the heads longer 35 than their transverse cross-sectional dimensions t in the plane of the widths of the heads. The heads of the fastenings are formed with their under sides arranged at an angle to the upper portions of the shanks 40 of the fastenings so as to overhang a portion of the stock into which they are driven. It is considered preferable that the under sides of the heads of the fastenings be positioned at right angles to the shanks of the 45 fastenings as indicated at 2 (Fig. 9). The heads may, however, be formed with their under sides inclined to the shanks of the fastenings as indicated at 3.

The fastenings D are inserted into the 50 welt C preferably successively and are arranged systematically so that the long dimensions of their heads are disposed at intervals transversely of the edge of the shoe, and substantially at right angles thereto, 55 the spacing of the fastenings being preferably obtained by effecting relative movement of the work and the fastening inserting instrumentality alternately with the fastening inserting operations of the fastening inserting instrumentality. It is recognized, however, that the practice of the invention is not restricted to the particular manner of assembling the pieces of shoe stock described above or to the insertion of the 60 fastenings successively, since the parts may 65

be otherwise assembled or a plurality or all of the fastenings forming the seam may be inserted simultaneously within the scope of the invention. A machine for inserting fastenings of the kind illustrated from a string 70 of such fastenings is disclosed in the application of George Goddu and Fred L. MacKenzie, Serial No. 137,571, filed Dec. 18, 1916.

The shoe is completed, after the attachment of the welt to the upper and insole in the manner above described, by attaching an outsole E to the welt C. This is done by means of a seam composed of metallic fastenings D inserted in accordance with this 75 invention with the long dimensions of their heads disposed transversely of the edge of the outsole. The space between the outsole and insole is filled in the usual manner.

As shown, the fastenings D are of a form 80 commonly denominated string nails having their heads projecting from one side only of their shanks, and the fastenings are so arranged that their heads extend from the sides of their shanks toward the outer edge 85 of the welt and of the outsole. By reason of such arrangement of the fastenings, a very tight seam is produced. Moreover, any stress 90 exerted on the outer edge of the welt or outsole tending to loosen either of the seams or to rip the welt or outsole over the heads of the fastenings is resisted to the maximum degree by the projecting heads of the fastenings. By reference to Fig. 2, it will be 95 seen that any stress exerted on the outer 100 edge of the welt C or outsole E will be transmitted directly to the under surfaces K of the heads of the fastenings, which, as previously stated, are arranged at such an angle to the upper portions of the shanks of the 105 fastenings that the heads of the fastenings overhang a portion of the stock into which they are inserted. Fastenings arranged in the manner above described for attaching a welt may have their heads extended even 110 beyond the plane of the edge of the insole indicated by the line x—x in Fig. 2. As illustrated in Fig. 2, the fastenings D of the welt attaching seam are clinched in a direction away from the edge of the insole, permitting the fastenings to be driven very close to the edge of the insole and still be 115 strongly clinched into the material of the insole. The more closely the fastenings may be driven to the edge of the insole and still be firmly clinched, the more closely the free 120 ends of the heads of the fastenings may be brought to the edge of the welt, and the tighter is the seam that is formed by the fastenings. It will be noted that a fastening 125 of the kind illustrated will resist to the greatest degree a force exerted in the direction of the head of the fastening on the side of the shank of the fastening from which the head extends, hereinafter sometimes 130

called the front side of the fastening and will resist effectively a force exerted in the direction of the head of the fastening on either of the two adjacent sides of the fastening, and will resist in the smallest degree a force exerted in the direction of the head of the fastening on the side of the fastening opposite that from which the head of the fastening extends hereinafter sometimes referred to as the back side and indicated at L in Figs. 2 and 4. Fastenings positioned in accordance with the present method have their heads extending from the sides of their shanks along which a force tending to rip the welt or outsole over the heads of the fastenings is most likely to be exerted and so that any other stress which may tend to pull the welt or outsole away from the upper and insole will be exerted along the sides of the fastenings adjacent to the side from which the head extends and so that no stress can be exerted along the sides of the fastenings opposite those from which the heads extend.

25 Although the fastenings have been hereinbefore described as being of the form wherein the heads extend from one side only of their shanks and as being arranged with their heads extending from the sides of their shanks toward the edge of the welt or outsole, the invention in certain of its aspects is not limited to these features. The fastenings may be of a form having overhanging head portions on more than one side of their shanks; for example, they may have head portions extending on opposite sides of their shanks, but in such case one of such portions of the head will extend from the side of the shank towards the edge of the welt or outsole so as to overhang the welt or outsole. Moreover, the fastenings may be arranged with their head portions extending from the sides of the fastenings away from the outer edge of the welt or outsole. The long dimensions of the heads and shanks of the fastenings would then extend transversely of the edge of the welt or outsole, resulting in the fastenings being spaced apart by the maximum distance. A relatively large space is thus afforded between adjacent fastenings compared to the small dimensions of the heads and shanks of the fastenings, the spaces being large enough to permit ready flexing of the parts in which the seam is formed between the adjacent fastenings. It is recognized that the principles of the invention can be applied in various ways, particularly as regards the shape and arrangement of the fastenings, to achieve the results of the invention either wholly or in part, for which reason the scope of the invention is intended to be limited only by the appended claims.

60 The systematic arrangement of the fastenings whereby all the fastenings have the

long dimensions of their heads disposed transversely of the edge of the welt or outsole is an important feature of the invention. If some of the fastenings of the seam are not arranged in accordance with the invention, the seam will not only be impaired at such points, but a portion of the seam which is tight and strong may be opened by reason of the opening of a weaker portion of the seam. Moreover, if one part of the seam is not readily flexible in the direction of the seam to accommodate itself to the movement of the foot of the wearer, the advantages obtained by making other portions of the seam readily flexible are in great part lost.

Although the points of the fastenings of the welt attaching seam are preferably clinched in a direction away from the edge of the insole, and the points of the fastenings of the outsole attaching seam are preferably clinched in a direction away from the edge of the welt, as shown at H in Figs. 2 and 4, many of the advantages of the invention may be obtained if the points of the fastenings are clinched in other directions, for example, in the line of the seam as indicated at h in Fig. 3 or toward the edge of the insole or welt instead of away from it.

As illustrated in Fig. 4 of the drawings, 95 the outsole E is directly attached to the upper B and insole A by a metallic seam formed in accordance with the invention. The heads of the fastenings extend beyond the plane of the edge of the insole indicated by the line y—y. In this application of the invention also, the points of the fastenings are preferably clinched in a direction away from the edge of the insole, as shown, and the fastenings are arranged with their backs L faced away from the adjacent edge of the outsole toward the body of the outsole, which, of course, extends from one side of the shoe to the other so that no stress can be exerted on the outsole which would tend to rip the same over the backs of the heads of the fastenings. Also, by reason of the long dimensions of the heads of the fastenings extending substantially transversely of the edge of the outsole leaving 100 comparatively large portions of the tread face of the outsole between the heads of the fastenings, ready flexure of the outsole is permitted between the heads of the fastenings.

Fig. 5 illustrates the application of the invention to heel seat nailing. In this application of the invention, the fastenings D are inserted through the heel seat of the outsole E, the upper B, and the insole A to 115 form a seam of spaced fastenings for attaching the heel seat to the upper and insole.

After the attachment of the heel seat to the upper and insole, the heel is secured to the heel seat by nails which pass within 120 130

the curve defined by the heel seat nails. The heel and heel seat are then trimmed. The trimming tool has a runner which moves in the angle formed by the upper surface of the margin of the heel seat and the upper B operating to guide and position the tool properly during the heel trimming operation. This runner has a tendency to loosen the seam which attaches the heel seat to the upper and insole. This tendency of the runner to loosen the seam is accentuated by the pressure of the trimming tool on the contour edge of the heel, which is transmitted to the heel seat through the heel attaching nails. The resultant loosening of the seam, when the heel seat is attached by known methods, frequently causes imperfect operation of the heel trimming tool. The finished heel, therefore, is frequently rough and unsymmetrical, and, in addition, the loose seam at the heel seat detracts from the wearing qualities of the shoe.

When the heel seat is attached to the upper and insole in accordance with this invention, the force exerted by the runner and trimming tool is transmitted directly to the under sides of the overhanging heads of the fastenings in such manner that no loosening of the seam takes place during the operation of trimming the heel. The heel trimming operation is thereby rendered more perfect resulting in the production of a smooth symmetrical heel, and the wearing qualities of the shoe are unimpaired.

By reference to Fig. 7 it will be seen that when a heel seat is attached by fastenings inserted in accordance with the present invention, a wide strip of the sole near its margin lying within the broken lines *c-c* and *d-d* of Fig. 7 is maintained against flexure in a direction transverse to the line of the seam and the edge of the sole. This portion of the outsole extends close to the edge of the sole leaving only a small unsupported strip between the line *d-d* and the edge of the sole. The portion of the sole between the lines *c-c* and *d-d* is so large as compared with the portion between the line *d-d* and the edge of the sole that the last-named portion of the sole, which is not directly supported, is itself substantially inflexible in the direction transverse to the line of the seam, and will not bend along the line of the seam.

The attachment of a heel seat by means of string nails inserted in accordance with known methods is illustrated diagrammatically in Fig. 8. A narrow strip intervening between the lines *a-a* and *b-b* is maintained against flexure transversely of the line of the seam and a wide strip between the line *b-b* and the edge of the shoe sole is left unsupported. The unsupported margin of the sole bends back easily and tends to fold along the narrow line of the seam in

the operation of the heel trimming tool. Such a seam is not tight or strong enough to prevent it from being opened up in the trimming operation.

It will be noted that although fastenings 70 inserted in accordance with this invention form a seam which maintains the margin of the welt or outsole against flexure in a direction transverse to the edge of the sole, the capacity of the welt or sole to flex in the 75 direction of the seam is increased by reason of the larger spaces between the fastenings and the small dimensions of the heads of the fastenings in the line of the seam. Flexure of the sole in a direction transverse to the 80 edge of the sole is undesirable because it tends to open up the seam. It is, however, very desirable that the sole be readily flexible in the direction of the seam to accommodate itself to the movement of the foot of 85 the wearer.

The fastenings D may be inserted into the welt or outsole in inclined relation to the surface of the welt or outsole in order that the overhanging heads of the fastenings may 90 be brought closer to the edge of the outsole with the points of the fastenings located far enough within the edge of the insole to permit a firm clinch to be effected. In nailing heel seats, the free ends of the heads of the 95 fastenings are spaced at such a distance from the untrimmed edge of the sole that they will extend nearly to the edge of the sole when trimmed, but will not be struck by the trimming knives.

In the application of the improved method to channel nailing around the toe of the shoe, the seam formed in accordance with this invention may take the place of the stitched seam sometimes used or it may be employed 105 to reinforce the stitched seam. By reference to Fig. 6, it will be noted that the outsole E is channeled at F, and the fastenings D are driven so that their heads will lie in the channel in a position to be concealed in the 110 finished shoe by the flap G of the channel which is cemented down in the channel subsequently to the insertion of the fastenings. The fastenings D are herein illustrated as inclined similarly to those shown in Fig. 5. 115

Having thus described my invention, what I claim as new and desire to secure by United States Letters Patent is:

1. The method of connecting pieces of shoe stock by the use of a seam composed 120 of single pronged metallic fastenings having their heads relatively long as compared to their widths, which consists in assembling the pieces of shoe stock, driving the fastenings into the pieces of shoe stock with the 125 long dimensions of the heads of the fastenings disposed transversely of the edge of the stock, and clinching said fastenings in a direction transversely of the edge of the stock.

2. The method of connecting pieces of shoe stock by the use of a seam composed of metallic fastenings having their heads relatively long as compared to their widths, which consists in driving the fastenings through the pieces of shoe stock with the long dimensions of the heads of the fastenings disposed systematically substantially at right angles to the edge of the stock, and clinching the points of the fastenings into the material of the stock in a direction away from the edge of the stock.
3. The method of connecting pieces of shoe stock by the use of a seam composed of metallic fastenings having their heads projecting from one side only of their shanks and relatively long as compared to their widths, which consists in driving the fastenings through the pieces of shoe stock with the long dimensions of the heads of the fastenings disposed transversely of the edge of the stock and with the heads of the fastenings projecting from their shanks toward the adjacent edge of the stock, and clinching the points of the fastenings into the material of the stock in a direction away from the adjacent edge of the stock and on the opposite sides of the shanks from those from which the heads project.
4. The method of connecting an outsole to a piece of shoe stock for bottoming shoes by the use of a seam composed of metallic fastenings each having only a single shank and each having a head of relatively great length as compared to its width, which consists in driving the fastenings through the outsole and the piece of shoe stock so arranged that the long dimensions of the heads of the fastenings are disposed transversely of the edge of the outsole, and clinching the points of the fastenings into the material of the piece of shoe stock transversely of the edge of the stock.
5. The method of connecting pieces of shoe stock for bottoming shoes which consists in assembling an insole, an upper, and a welt, connecting them together by driving metallic fastenings having heads of relatively great length as compared to their widths through said welt, upper, and insole with the long dimensions of the heads of the fastenings disposed transversely of the edge of the welt, applying an outsole to the assembled insole, upper, and welt, and attaching the outsole to the projecting portion of the welt by a seam composed of metallic fastenings having heads of relatively great length as compared with their widths and arranged with the long dimensions of their heads disposed transversely of the edge of the outsole.
6. The method of connecting a welt to an upper and insole by the use of a seam composed of metallic fastenings having heads of relatively great length as compared to
- their widths, which consists in assembling the welt, upper and insole, and driving the fastenings into the welt, upper and insole so arranged that the long dimensions of the heads of the fastenings are disposed transversely of the edge of the welt.
7. The method of connecting an outsole to the welt of a shoe by means of a seam composed of metallic fastenings having heads of relatively great length as compared to their widths, which consists in driving the fastenings through the outsole and welt systematically arranged so that the long dimensions of the heads of the fastenings are disposed transversely of the edge of the outsole, and clinching the points of the fastenings in a direction toward the upper.
8. The method of connecting pieces of shoe stock by the use of a seam of string 85 nails having heads of relatively great length as compared to their widths projecting from their shanks and formed with their under sides arranged substantially at right angles to the shanks of the nails, which consists in assembling the pieces of shoe stock, and driving the nails into the pieces of shoe stock so arranged that the long dimensions of their heads are disposed substantially at right angles to the edge of the stock and 95 the nail heads overhang a strip of the stock between the line of the seam formed by the nails and the adjacent edge of the stock.
9. The method of connecting pieces of shoe stock by the use of a seam composed 100 of metallic fastenings having heads of relatively great length as compared to their widths, and having shanks formed with their longest transverse cross-sectional dimensions in the plane of the long dimensions of the heads, which consists in assembling the pieces of shoe stock, and driving the fastenings into the stock so arranged that the long dimensions of the heads of the fastenings and the longest 110 transverse cross-sectional dimensions of the shanks of the fastenings are disposed transversely of the edge of the stock.
10. A shoe having a sole portion and an upper portion connected by a seam composed of single pronged metallic fastenings, each fastening having a head of relatively great length as compared to its width, said fastenings being arranged with the long dimensions of their heads extending transversely of the seam.
11. A shoe made up from a plurality of pieces of stock connected by a seam composed of metallic fastenings, each fastening having a single shank and a head relatively 125 long as compared to its width, said fastenings being arranged with the long dimensions of their heads transversely of the seam, and each fastening being clinched in a direction transversely of the stem.

12. An article of manufacture made up of a plurality of sheets of material connected by a seam composed of driven metallic fastenings, each fastening having its head extending upon one side only of its shank and of relatively great length as compared to its width, the fastenings being arranged

with the long dimensions of their heads transversely of the seam, each fastening being clinched in a direction transversely of the seam.

In testimony whereof I have signed my name to this specification.

PHILIP H. FRAHER.
